(57) **CLAIM**

The ornamental design for a multiple blade peeler, as shown and described.

DESCRIPTION

FIG. 1 is a front, top perspective view of a multiple blade peeler showing our design therefor;

FIG. 2 is a front, bottom perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a top plan view thereof; and,

FIG. 8 is a bottom plan view thereof.

The portions shown in phantom line are environment only and form no part of the design.
